CAN END LINING MACHINE

Matthew L. Heald, Portland, Maine, and Harvey L. Bryant, Roselle, N. J., assignors to American Can Company, New York, N. Y., a corporation of New Jersey

Application July 25, 1935, Serial No. 33,172

11 Claims. (Cl. 113—80)

The present invention relates to liquid applying machines such as can end lining machines and has particular reference to novel devices for effecting an unobstructed and non-interfering liquid conveying connection between a supply of liquid material contained in a stationary reservoir and a rotating liquid applying mechanism such as a compound lining head in can end lining machines.

10 In its preferred embodiment the invention contemplates the transmission of liquid lining material to liquid conducting means rotating with a revolving applying head which carries a movable lining nozzle connected with the liquid conducting means. The invention is readily applicable to can end lining machines having these characteristics but in its broader aspects may be utilized in connection with any similar type of liquid applying machine such as filling machines or spraying machines or the like which have rotatable or rotating liquid receiving or dispensing members which are best served from a stationary supply tank or reservoir.

An object of the invention is the provision in 25 a can end lining machine wherein the can end stands still and the nozzle is carried in a rotating head and caused to travel around the can end contour over the channel or flange to be lined, of devices wherein a liquid lining material is conducted from a stationary tank or reservoir to the nozzle while the head is rotating.

Another object is the provision in a machine 30 of this character, of devices for connecting the stationary tank with the nozzle on the rotating head wherein packing glands are dispensed with and wherein free flowing unrestricted passageways are provided for highly volatile liquid lining materials or the like so that coagulation or accumulation of the material in the passageways is 35 reduced to a minimum.

Another object is the provision of such a lining machine wherein the supply tank may be positioned at any available place on or near the machine and wherein it is connected with the nozzle 40 on the rotating head by flexible liquid conducting connections which are adapted to be rotated in timed relation with the rotating head.

Another object is the provision of devices 45 wherein such a rotatable flexible connection may be suitably supported while rotated.

Numerous other objects and advantages of the invention will be apparent as it is better understood from the following description, which, taken in connection with the accompanying drawing, 50 discloses a preferred embodiment thereof.

Referring to the drawing:

Figure 1 is a vertical sectional view of a lining machine embodying the instant invention, parts being broken away; and

Fig. 2 is a horizontal sectional view taken substantially along the line 2—2 in Fig. 1.

The preferred embodiment of the invention disclosed in the drawing comprises a mechanism having a housing or frame 11 which may be a part of a can end lining machine or the like. The 10 housing supports a rotatable lining head 12, which receives liquid lining material, through a flexible tubular connection communicating with a supply of the lining material 13, contained in a sealed stationary tank or reservoir 14 which may 15 be a part of the machine or may be a detached separate unit located near the machine.

The part of the connection associated with the lining head 12 comprises a liquid conducting element or tube 15 which is closed at its bottom 20 end and which extends down through the head projecting below it and rotating with it but is independently rotated or shifted relative thereto as will be hereinafter explained. The upper end of the tube is threadedly secured in the lower 25 end of a bushing 16, which is carried vertically in a bearing 17, formed in the top of the housing 11. The bushing is supported in the bearing 17 by a bushing flange 18 which engages the top of the bearing, and by a collar 19, which is threadedly 30 secured to the projecting lower end of the bushing, and which engages the bottom of the bearing.

The bushing 16 has a bore 21 which is in alignment with the bore of the tube 15. At its upper end the bore 21 is widened to connect with a larger 35 diameter nipple 22 which is formed on the top of the bushing. To this nipple one end of a flexible tube or hose 23 is secured by a clamping strap 24.

The flexible tube 23 leads to the tank 14 and is the connection between the rotating head and 40 the stationary tank. At the tank end of the tube, it is secured over a nipple 27 by a clamping strap 28. The nipple is threadedly connected to the upper end of a vertical pipe 31, which is carried in a tank cover 32, bolted and sealed to the 45 top flange of the tank 14. The lining material or compound used on the lining of can end flanges is usually of a highly volatile nature for quick drying purposes and therefore it is desirable to provide a sealed tank for holding it. The pipe 31 50 extends down into the tank to adjacent its bottom with its lower end immersed in the lining material 13.

The pipe 31 is mounted in a sleeve 34, which at 55 its upper end is secured to a flange 35 formed on

the bottom of the nipple 27. The sleeve in turn is journaled in a bearing 36 which is carried in a boss 37 formed in the tank cover 32. This part of the tank mechanism is hermetically sealed by a pair of standard sealing rings 38 which are mounted on the lower end of the sleeve 34, engaging within a counterbore 39 formed in the bottom of the boss 37 and held against the lower end of the bearing 36 by a collar 41 which 10 threadedly engages the lower end of the sleeve.

In the machine illustrated in the drawing the tank 14 is shown as a detached separate unit located near the machine and elevated just above the lining head 12. It should be understood, 15 however, that the tank may be placed in any convenient location which can be reached by the flexible tube 23. As an example, the tank may be located directly over the lining head 12 with the flexible tube extending straight up and 20 the pipe 31 emerging from the bottom of the tank instead of its top. To meet the requirements of the preferred location illustrated the flexible tube 23 is curved in a semi-circle and is supported on a plurality of ball bearing units 45, which are 25 carried in brackets 46, mounted on the outer ends of spider arms 47. The arms are secured to a spider frame which is screwed to the top of a gear casing 49, surrounding the tank end of the flexible tube 23 and mounted on top of the tank 30 cover 32.

The flexible tube 23 is rotated with the lining head 12 through its connection with the bushing 16 and the tube 15. To prevent torsional strains being set up in the rotating flexible tube the tank 35 end of the tube is rotated in timed relation with the lining head by a chain and gear connection. For this purpose a driving sprocket 51 is secured to the top of the bushing flange 18 which engages and drives an endless chain 52 which in turn drives a sprocket 53 adjacent the tank end 40 of the tube.

The sprocket 53 is secured to the hub of a gear 54 and both sprocket and gear are mounted on a shouldered stud 55 which is carried in one end of a bracket arm 56. The other end of the arm is formed with a flanged hub 57, mounted on the 45 outside of the bearing 36, and is secured to the top of the boss 37 by cap screws 58. The gear 54 meshes with and drives a gear 61 which is formed on top of the sleeve 34, providing a means of rotating the sleeve in its bearing 36. Through this driving connection the pipe 31 and the flexible tube 23 are rotated with the head 12 and tube 15, the pipe and tubes forming an unrestricted liquid conveying passageway from the tank to the head without utilizing any packing glands or forming any obstructions in the line which may tend to accumulate or coagulate or interfere with the free passage of the liquid lining 50 material as it passes through these conduits.

The liquid 13 is forced through this passage by air pressure which is exerted on the surface of the liquid and which is brought into the tank through a pipe 62 one end of which is threadedly secured in the tank cover 32 and communicating 55 with the tank interior. The other end of the pipe is associated with any suitable means of delivering a supply of compressed air, such as a compressor or the like.

The head 12 may be any kind of a rotating head 60 for dispensing a liquid or semi-liquid such as used on can end lining or can filling or spraying machines, the preferred head illustrated in the drawing being of the end lining type. It is carried on a sleeve 71 which surrounds the lower

end of the liquid conducting tube 15 and which is rotatably mounted in a bearing 72 formed in the housing 11. At its upper end the sleeve is keyed to a gear 73 which rests on top of the bearing thus vertically supporting the head. The gear 73 meshes with a driving gear 74 which is associated with any suitable means of rotating it in timed relation with the sprockets and gears hereinbefore described. It is this system of sprockets and gears which rotates the head 12 10 and the tubes connecting with the stationary liquid tank just described.

The lower end of the sleeve 71 is formed with a head body 75, which carries a liquid dispensing nozzle 76 which is connected with the lower end 15 of the tube 15, communicating with its interior, by means of a flexible pipe 77. The nozzle is mounted on a system of compound lever arms which move it relative to the rotating head body. The nozzle is fixed on one of these arms indicated by the character 78, the arm being pinned to the lower end of a shaft 79 which is carried in a bearing 80 formed as a part of a second lever arm 81. The upper end of the shaft 79 is formed as an arm 82 which carries a cam roller 83 engaging within a cam groove 84 of a stationary cam 85, bolted to the under side of a flange 86 formed at the lower end of the sleeve 72.

The arm 81 is pinned to the lower end of a shaft 91 which is mounted in a bearing 92 formed 30 as an integral part of the head body 75. Like the shaft 79, the upper end of the shaft 91 is formed with an arm 93 which carries a cam roller 94 engaging within another outer cam groove 95 formed in the cam 85 adjacent and 35 above the groove 84.

As the head 12 is rotated by the gears 73, 74 it carries the described arms around with it and moves the rollers in the grooves of the stationary cam. The grooves are so shaped as to move 40 the nozzle through a predetermined path of travel over the top of and following the contour of the liquid lining receiving channel or flange of a can end 96 to be lined. For irregular shaped can ends this travel of the nozzle causes it to shift 45 radially relative to the head body 75 and it is this shifting which effects rotating movement of the tube 15 relative to the head.

The can ends 96 may be individually fed into the machine between spaced guide bars 97 which 50 are secured to the top of a frame 98 on which the housing 11 may be supported. The can ends are positioned over a lifter pad 99 which is disposed directly under the center of the rotating head 12 in a bearing 101 formed in the frame 98. 55

The lifter pad 99 with its positioned can end is raised by any suitable mechanism actuated in timed relation with the other moving parts of the machine and thus presents the can end to the traveling nozzle 76 for lining. This lifting action 60 unlocks a nozzle operating sleeve 105, the lower end of which extends below the head body 75 and is formed with a laterally projecting finger 106. The finger is engaged by a hooked lever 107, which is pivotally secured to a bracket arm 65 108 formed on the head body and which is connected by a link 109 to a plunger 111, yielding held in the closed bottom end of the liquid conducting tube 15. As the can end is raised it engages the plunger 111, moving it up into the 70 tube 15 and pivots the hooked lever 107 away from the locking finger 106.

The nozzle operating sleeve 105 is mounted on the tube 15, inside of the sleeve 71, and extends up through the sleeve projecting above it, where 75

it is slidably keyed to the tube 15. The upper end of the sleeve 105 carries a spring held collar 114 which engages the end of a lever 115 which is moved in time with the raising of the lifter pad 99. As soon as the finger 106 of the sleeve 105 is released, the lever raises the sleeve and opens the nozzle permitting the lining material to flow out into the can end channel. This is effected by connection of the nozzle needle valve stem 118 with a bifurcated finger 117 which extends laterally from the lower end of the sleeve 105 disposed opposite and below the finger 106 and which engages with the needle valve stem.

The bifurcated finger 117 also engages the upper part of the nozzle which acts as the driving means for turning the sleeve 105 and tube 15 with the head. Thus the sleeve 105 and tube 15 move with the nozzle which is directly carried on the head body 75. It is this indirect connection between the head body and the sleeve 105 which causes relative movement between them as the nozzle is radially shifted by the cam grooves 84, 85.

The means for imparting rotation to the desired interconnected parts of the machine may be briefly recapitulated as follows:

Driving gear 74 drives gears 73 which is keyed to sleeve 71 constituting a unitary part of the head member 75. The latter through its integral bearing 92 rotates shaft 91 bodily about the axis of the tube 15. Shaft 91 carries arm 81, bearing 80, arm 78 and nozzle 76 bodily around said circular path. The valve stem 118 of the nozzle which is engaged by the outer bifurcated end of finger 117 rotates the latter and the nozzle operating sleeve 105 of which said finger is an integral part. Sleeve 105 is slidably keyed to the tube 15 to permit vertical movement of the sleeve relative to the tube, at the same time imparting rotation to the tube. Bushing 16 threaded to the upper end of tube 15 is thereby rotated and with it the driving sprocket 51, the latter in turn through chain 52 driving sprocket 53, gears 54 and 61, the latter being rigidly connected to the pipe connection 31 to rotate the latter within the tank 14. The flexible tube 23 is secured at its opposite ends to the bushing 16 and pipe 31 respectively, rotation being thereby imparted to said flexible tube at each end to insure against torsional strains.

The present invention is similar as to its general objects, as well as in several respects, to that disclosed in United States Patent No. 2,052,568, for Can end lining machine, issued September 1, 1936, to Matthew L. Heald, one of the joint applicants herein, particularly as to the manner of rotating the lining head and causing the liquid dispensing nozzle to follow a predetermined irregular path of travel conforming to the configuration of the can end to be lined. The instant invention, however, provides certain improvements over that disclosed in said issued patent.

In lining can ends with certain relatively highly viscous rubber cements or compounds by means of the machine disclosed in said issued patent, it has been found that there is a tendency for the cement to be applied in greater quantity, for example, at the curved portions of the can end channel than along the straight portions thereof, thereby tending to detract from uniform application of the compound around the peripheral channel of the end to be lined. This disadvantage has been found to be due largely to the fact that in said patent the hollow vertical

shaft 220, which corresponds in its purpose to applicants' rotating tube 15, is stationary insofar as rotary movement is concerned. The same is true in the patent of the flexible tube 226 leading from the desired source of lining compound and which tube communicates with the upper end of the shaft 220 and corresponds to applicants' rotatable flexible tube or hose 23 as disclosed herein which is communicably connected with the stationary lining compound tank 14. By rotating the instant liquid conducting tube 15 which communicates at its lower end with the liquid dispensing nozzle 76, it has been found that the viscosity of certain rubber cements may be more readily controlled in actual practice, particularly as to the uniform application of such cement to the can end channel. It is to obtain rotary movement of the tube 15, as distinguished from the corresponding stationary hollow vertical shaft 220 of the said issued patent, and yet to provide for communication of said rotating tube with a stationary tank for holding the lining compound, that the present invention is primarily designed.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. In a machine for lining can ends, the combination of a rotating head carrying a can end lining nozzle, a stationary tank for holding a supply of liquid lining material, means in said tank for conveying said liquid therefrom, rotatable means associated with said head and connected with said nozzle for conducting said liquid to said nozzle, and means rotatable on its axis for connecting said rotatable liquid conducting means with said liquid conveying means.

2. In a machine for lining can ends, the combination of a rotating head carrying a can end lining nozzle, a stationary tank for holding a supply of liquid lining material, means in said tank for conveying said liquid therefrom, rotatable means associated with said head and connected with said nozzle for conducting said liquid to said nozzle, and means rotatable on its axis for connecting said rotatable liquid conducting means with said liquid conveying means, all of said means rotating in unison with said head.

3. In a machine for lining can ends, the combination of a rotating head carrying a can end lining nozzle, a stationary tank for holding a supply of liquid lining material, means in said tank for conveying said liquid therefrom, rotatable means associated with said head and connected with said nozzle for conducting said liquid to said nozzle, means rotatable on its axis for connecting said rotatable liquid conducting means with said liquid conveying means, and means for rotating each of said rotating and rotatable means in timed relation with said head.

4. In a machine for lining can ends, the combination of a rotating head carrying a can end lining nozzle, a stationary tank for holding a supply of liquid lining material, means in said tank for conveying said liquid therefrom, rotatable means associated with said head and connected with said nozzle for conducting said liquid to said nozzle, means rotatable on its axis for

connecting said rotatable liquid conducting means with said liquid conveying means, and means for rotating said liquid conducting means and said connecting means in timed relation with said head.

5. In a machine for lining can ends, the combination of a rotating head carrying a can end lining nozzle, a stationary tank for holding a supply of liquid lining material, rotatable means 10 in said tank for conveying said liquid therefrom, rotatable means associated with said head and connected with said nozzle for conducting said liquid to said nozzle, means rotatable on its axis for connecting said liquid conducting means with 15 said liquid conveying means for conveying said liquid from said tank to said conducting means, and means for rotating said liquid conducting means, said conveying means and said connecting means in unison and in timed relation with 20 said head.

6. In a machine for lining can ends, the combination of a rotating head carrying a can end lining nozzle, a stationary tank for holding a supply of liquid lining material, means in said 25 tank for conveying said liquid therefrom, rotatable means associated with said head and connected with said nozzle for conducting said liquid to said nozzle, flexible tubular means connecting said liquid conducting means with said liquid 30 conveying means, means for rotatably supporting said flexible tubular means intermediate its ends and means for rotating said liquid conducting means and said tubular means in timed relation with said head.

35. 7. In a machine for lining can ends, the combination of a rotating head carrying a can end lining nozzle, a stationary sealed tank for holding a supply of liquid lining material, means in said tank for conveying said liquid therefrom, 40 rotatable means associated with said head and connected with said nozzle for conducting said liquid to said nozzle, means rotatable on its axis for connecting said liquid conducting means with said liquid conveying means, and means associated with said sealed tank for causing said 45 liquid to flow through said conveying, conducting and connecting means into said nozzle.

8. In a machine for dispensing a liquid, the combination of a stationary liquid supply reservoir, a rotating dispensing mechanism having means for dispensing said liquid to a place of deposit, means rotating with said mechanism for conducting said liquid to said dispensing means, and means rotating on its axis in synchronism with said mechanism and communicably connected with said liquid conducting means and with said reservoir to convey said liquid from 10 said reservoir to said conducting means.

9. In a machine for lining can ends, the combination of a rotating head carrying a can end lining nozzle, a stationary tank for holding a supply of liquid lining material, means in said tank for conveying said liquid therefrom, rotatable means associated with said head and communicating with said nozzle for conducting said liquid to said nozzle, means rotatable on its axis for connecting said rotatable liquid conducting 20 means with said liquid conveying means, and means for rotating said head and said liquid conducting and conveying means in timed relation.

10. In a machine for lining irregularly shaped can ends, the combination of a rotating head 25 carrying a can end lining nozzle, a stationary tank for holding a supply of liquid lining material, means in said tank for conveying said liquid therefrom, rotatable means associated with said head and connected with said nozzle for conducting said liquid to said nozzle, means for moving said nozzle radially relatively to said head as it rotates with the head, means for turning on its axis said liquid conducting means relative to said head, and means for connecting said 30 liquid conducting means with said liquid conveying means for conveying said liquid from the latter to the former.

11. In a machine for dispensing a liquid, the combination of a stationary liquid supply tank, 40 a rotatable dispensing nozzle, an axially rotatable flexible liquid conduit communicably connected with said tank and with said nozzle, and means for rotating said conduit in timed relation with the rotation of said nozzle.

MAITTHEW L. HEALD.
